UNITED STATES PATENT OFFICE.

WALTER P. PRALL, OF COLUSA, CALIFORNIA.

SULKY HAY-RAKE.

SPECIFICATION forming part of Letters Patent No. 256,735, dated April 18, 1882.

Application filed July 28, 1881. (No model.)

To all whom it may concern:

Be it known that I, WALTER P. PRALL, of Colusa, in the county of Colusa and State of California, have invented certain useful Improvements in Sulky Hay-Rakes, of which the following is a specification.

Figure 1 is a plan view of my improvement. Fig. 2 is a front elevation of the same. Fig. 3 is a sectional side elevation of the same, taken 10 through the line $x x$, Figs. 1 and 2. Fig. 4 is a sectional elevation, showing the foot-lever and its attached rods unlocked.

Similar letters of reference indicate corresponding parts.

15 The object of this invention is to facilitate the operation of raking hay and promote convenience in operating and controlling the hay-rake.

The invention consists in the combination, 20 with the carriage and the upper bar of the rake-head, of the connecting-bar, the foot-lever, and the draw-bar, whereby the draft-strain will hold the rake-teeth to their work and can be made to raise the rake-teeth and dump the 25 collected hay; and, also, in the combination, with the carriage and the upper bar of the rake-head, of the connecting-bars, the connecting-lever, and the hand-lever, whereby the 30 rake-teeth can be raised by hand-power to unlock the foot-lever and allow the draft-strain to dump the collected hay, as will be herein-after fully described.

A are the wheels, B the axle, and C the 35 thills, which parts form the rake-carriage. To the upper side of the axle B is attached a rod or bar, D, to which are attached the upper ends of the rake-teeth E. The rake-teeth E are formed of spring-wire curved in the ordinary manner. From the bar. D the rake- 40 teeth E pass up to and are coiled around a bar, F, placed above and parallel with the bar D. By this construction the rake-teeth are raised above the axle to form more space for the collected hay and to avoid the tendency of the 45 rake-teeth to rise and slip over the hay.

To the upper bar, F, at or near its middle part, is attached the end of the short connecting-rod G, the lower end of which is hinged to a short lever, H, pivoted to a rod, I, attached 50 to the thills C. To the lower end of the lever

H is hinged the rear end of a short connecting-rod, J, the forward end of which is hinged to the lower end of a hand-lever, K. The hand-lever K is pivoted to the thill C, and its upper end projects into such a position that it 55 can be conveniently reached and operated by the driver from his seat to raise the rake-teeth and discharge the collected hay.

To the middle part of the bar F is also hinged the upper end of a connecting-rod, L, the lower 60 end of which is hinged to the lower end of a lever, M, which is pivoted to a rod, N, attached to the thills C. The upper end of the lever M projects into such a position that it can be 65 readily reached and operated by the driver with his foot. To the foot-lever M is hinged the rear end of a rod, O, which passes through a keeper attached to the lower side of the forward cross-bar of the thills C, and to its forward end is pivoted the single-tree P, to which 70 the draft is applied. The hinging-point of the draft-rod O is arranged in such a position as to be in line with or a little above the pivoting-point of the lever M when the rake-teeth E are in working position, so that the draft-strain will lock the lever M and hold the said 75 rake-teeth to their work. With this construction, when the lever M is moved to bring the hinging-point of the draft-rod O below the pivoting-point of the foot-lever M, the draft-strain 80 will operate the said foot-lever and raise the rake-teeth E from the ground, discharging the collected hay. With this construction, the hand-lever K and the foot-lever M move in opposite directions toward each other when raising the rake-teeth E from the ground, so that the driver can use the power of hand and foot 85 to the best advantage in controlling the rake-teeth.

Q is the driver's seat, the standards R of 90 which are attached to the thills C or to rods attached to the said thills.

Having thus described my invention, I claim as new and desire to secure by Letters Patent—

1. In a sulky hay-rake, the combination, 95 with the axle B, bars D F, connected by the ends of teeth E, and the teeth E, of the connecting-rods G J L, connecting-lever H, hand-lever K, and foot-lever M, pivoted at N, and the pivoted draw-bar O and single-tree P, 100

whereby when the hinging-point of draw-bar O is brought below foot-lever pivot N the draft operates to raise the rake-teeth and discharge the load, substantially as shown and described.

5 2. In a sulky hay-rake, the combination, with the axle B, bars D F, placed one above the other, and the teeth E, of the rods G J L, connecting-lever H, hand-lever K, and foot-

lever M, whereby the rake is lowered by the combined hand and foot power of the driver, substantially as shown and described.

WALTER P. PRALL.
